UNITED STATES PATENT OFFICE.

JAMES F. ROWLEY, OF WINSTED, CONNECTICUT, ASSIGNOR TO THE HIGH-LAND MANUFACTURING COMPANY, OF SAME PLACE.

DESIGN FOR A CAN-OPENER.

SPECIFICATION forming part of Design No. 28,420, dated March 29, 1898.

Application filed August 25, 1897. Serial No. 649,538. Term of patent 7 years.

To all whom it may concern:

Be it known that I, JAMES F. ROWLEY, a citizen of the United States, residing at Winsted, in the county of Litchfield and State of Connecticut, have invented and produced a new and original Design for a Can-Opener; and I do hereby declare the following to be a full, clear, and exact description of the same, reference being had to the accompanying drawing, forming a part thereof.

As shown in the drawing, the leading or material feature of my design for a can-opener embodies the handle A of the configuration shown, which has flattened sides *a* and a tapered ferrule *a'*. It also includes the shank or bar B, which is rectangular in cross-section,

the end thereof farthest from the handle being shaped to present a curved portion B' and a rounded or cylindrical portion *b*, which is positioned at substantially right angles with the shank or bar B, and the terminal or end *b'* is tapered or pointed and positioned at right angles with the intermediate part *b*.

I claim—

The design for a can-opener, as herein shown and described.

In testimony whereof I affix my signature in presence of two witnesses.

JAMES F. ROWLEY.

Witnesses:

HARVEY L. ROBERTS,
WM. A. SWEET.
